UNITED STATES PATENT OFFICE.

WILLIAM HUBBARD, OF ROCHESTER, NEW YORK, ASSIGNOR, BY MESNE ASSIGNMENTS,
TO UNITED SHOE MACHINERY CORPORATION, OF PATERSON, NEW JERSEY, A COR-
PORATION OF NEW JERSEY.

HEEL.

1,273,492.

Specification of Letters Patent. Patented July 23, 1918.

Application filed July 27, 1916. Serial No. 111,739.

To all whom it may concern:

Be it known that I, WILLIAM HUBBARD, a citizen of the United States, residing at Rochester, in the county of Monroe and State of New York, have invented certain Improvements in Heels, of which the following description, in connection with the accompanying drawings, is a specification, like reference characters on the drawings indicating like parts in the several figures.

This invention relates to heels.

In the cycle of changes in footwear fashions, there is a periodic recurrence of popularity for fancy or ornamental heels, such for instance, as heels of the so-called Louis or ogee type. While these fancy heels are graceful and ornamental when new, they have heretofore not been durable and have deteriorated greatly in condition and appearance after a comparatively brief period of wear.

With these considerations in view, the prime object of the present invention is to provide a heel which can be built with graceful lines and, will, at the same time, be solid and durable in construction, while permanently preserving its original ornamental features even after a considerable period of wear.

With this object in view, an important feature of the invention consists in the introduction into a heel of one or more layers or lifts of substantially non-fibrous rigid material. A wide range of materials may be utilized in this connection and eminently satisfactory results have been secured in practice by the use of both celluloid and sheet metal, such as aluminium. These rigid lifts may be inserted in the heel in any desired number and at any convenient time, but it has been found especially satisfactory to build them into the heel blank, one or more such lifts being placed at the heel seat end of the blank, and one or more at the top lift end, the heel building nail or nails being driven through the entire assemblage and securing the parts firmly together. When such a heel is compressed and molded, the auxiliary lifts being non-fibrous and rigid, as compared with the fibrous material, of which the body of the heel is built, the joints or cracks in the surface of the heel are closed up, and the tendency of the heel to check is greatly reduced. The heel seat

end of the heel being faced with a rigid lift having smooth edges also facilitates the production of a neat and permanently tight joint between the heel and the sole of the shoe. It furthermore becomes possible to form in the heel compressing operation a series of indenting projections upon the heel which are pressed into the sole of the shoe in the heel attaching operation and effectively prevent any slipping of the heel relatively to the shoe under the pressure of the heelng machine.

While a heel of the Louis type has been selected for the purpose of illustration, it should be understood that the invention is applicable to heels of various other types and styles, and that its utility is not limited to a heel of the exact form shown in the accompanying drawings.

In the drawings:

Figure 1 is a perspective view of a compressed heel blank embodying the invention;

Fig. 2 is a view in side elevation of a fragment of the rear end of a shoe after the heel has been attached and the top lift applied;

Fig. 3 is a view similar to Fig. 2, illustrating a modification in the arrangement of the auxiliary lifts.

The numeral 10 indicates the body portion of a heel formed of leather, leatherboard or any other fibrous material, herein generically referred to as leather stock, such as is commonly used in heel manufacture. The usual leather or rubber top lift is indicated at 12 and may be attached to the heel by a nail or screw 14 or any other suitable means. Auxiliary lifts 16 and 18 are built upon the heel seat and top lift ends of the heel respectively, as illustrated in Fig. 1, the whole assemblage being usually secured together by a heel building nail 20 which passes through and is clenched upon the lift 16. The auxiliary lifts 16 and 18 may be aluminium, brass, celluloid, imitation ivory or any other suitable, comparatively rigid, non-fibrous, material. They are of sufficient size so that their edges will be exposed, wholly, or in part, when the heel is finished. In order to secure an ornamental effect, the auxiliary lift or lifts preferably have a color contrasting with that of the body portion 10 of the heel.

The blank illustrated in Fig. 1 has been

- 2
- compressed and molded, and in the molding operation, projections 22 are formed upon the seat surface of the heel by a suitable 10 lift wear die in the heel compressor. At the same operation a size number 24 or any suitable ornamentation or lettering 26, may be formed. The projections and other designs molded upon the seat face of the heel indent the heel seat end of the outsole of the shoe and effectively prevent the heel from slipping relatively to the shoe under the pressure of the heelng machine, a difficulty which is frequently encountered when the surface of the heel is smooth. When the lift 16 is made of aluminum or other metal, the projections 22 may be covered with the metal, and when the lift is made of celluloid or other less ductile material, the conical portions of the projections may break out, leaving projecting spurs of leather or leatherboard which will also act effectively to prevent slipping.
- When the heel is compressed between the relatively rigid lifts 16, 18, held together by the heel building nail 20, there is a tendency to prevent the checking of the heel or the opening of the joints between the lifts of which it is composed, which is particularly difficult to overcome in the case of high heels having considerable pitch, where the heel nails cannot be driven close to the edge of the heel. Furthermore, when the base lift of the heel is made of leather, or, as is more common, of leatherboard, it is frequently more or less uneven and ragged around the edge, making it difficult to form a neat, tight, joint between the heel and the heel seat end of the sole 28. When the base lift of the heel, however, is made of aluminum, celluloid or other comparatively smooth and rigid material, a smooth, regular surface may be easily formed upon its periphery and it is a simple matter to secure a permanently tight and neat joint between the heel and the sole.
- The heel may be attached to the shoe by any one of the usual well-known means, such for instance, as heel attaching nails 30, driven through the auxiliary lift or lifts, drawing the heel tightly together and holding it firmly between these relatively rigid lifts or plates.
- A substantial advantage is obtained by the use of either one of the lifts 16, 18 alone, but it is preferred to use both, in order to obtain the utmost possible benefit. The lift 18 serves as an indicating means to warn the wearer of the shoe to have a new top lift placed upon the heel when the original top lift is worn down nearly to the auxiliary lift, and also prevents the edge of the heel from becoming ragged and unsightly, a very common occurrence with ordinary heels after they have been wet.
- The auxiliary lift or lifts are preferably made of a homogeneous material, uniformly colored throughout, so that the ornamentation afforded by their exposed edges, which preferably contrast in color with the remainder of the heel, is permanent, no matter how long the heel may be worn.
- For the purpose of variation in ornamental effect, a plurality of auxiliary lifts of different colors may be superposed, as illustrated at 31, 32 in Fig. 3, and one or more additional auxiliary lifts may be introduced into the heel, as shown at 34, thus increasing the solidity and rigidity of the heel.
- From the foregoing it will be apparent that a heel of a type, for which there is at present a very large demand, has been produced, which is superior in construction, strength and durability to the heels heretofore in use and which is capable of a wide variety of ornamentation. The latter is a very important feature in connection with the types of footwear upon which heels of this type are commonly used, and the fact that the ornamentation is absolutely permanent and cannot be effaced by wear or rough usage, is a consideration of the greatest value and importance.
- It has been found by experience that heels embodying this invention can be trimmed, scoured and finished in the usual manner, the auxiliary lifts of various compositions or soft metals not interfering in any way with the operations upon the heel, so that the expense of embodying this invention in a heel is extremely small, as compared with the benefits derived from it.
- Having described the invention, what is claimed as new, and desired to be secured by Letters Patent of the United States is:—
1. A heel having a body portion composed of lifts of fibrous material, and an auxiliary metallic lift soft enough to permit its edge to be trimmed with those of the fibrous lifts, the edges of all of the lifts being exposed in the finished heel and the metallic lift being located next to the top lift.
  2. A heel having a body portion composed of lifts of fibrous material and a lift of an easily cut metallic substance at each end of the body portion to give strength to the heel, the edges of all the lifts being exposed in the finished heel.
  3. A heel comprising compressed leather stock lifts and a lift of substantially non-compressible material at the top lift end of the heel blank, a headed heel building nail extending through said lifts and having its head set against the non-compressible lift and its point clenched on the outer surface of the heel-seat end of the blank, and a top lift held against the non-compressible lift.
  4. A heel comprising compressed leather stock lifts and a substantially non-compressible lift at one end of the heel and a headed heel building nail extending through all

said lifts and its head set against the leather stock lifts and having its point clenched on the outer surface of the non-compressible lift and holding the lifts firmly together under compression.

5. A heel comprising compressed leather stock lifts and a substantially non-compressible lift at each end of the heel and a heel building nail connecting said two non-compressible lifts and clenched on the outer sur-

face of one of them to hold the compressed lifts under compression.

6. A compressed heel comprising a plurality of superposed lifts including a lift of non-fibrous substantially rigid material that 15 can be trimmed flush with the other lifts in the heel trimming operation.

In testimony whereof I have signed my name to this specification.

WILLIAM HUBBARD.
